United States Patent Office

Des. 179,339
Patented Dec. 4, 1956

179,339

LUMINAIRE

Philip B. Clark, Hales Corners, and Donald W. Harling,
Milwaukee, Wis., assignors to McGraw Electric Com-
pany, Milwaukee, Wis., a corporation of Delaware

Application April 30, 1956, Serial No. 41,247

Term of patent 14 years

(Cl. D48—31)

Fig.1

Fig.2

Fig. 1 is a perspective view of a luminaire embodying our new design; and

Fig. 2 is an elevational view thereof, the luminaire being symmetrical about its vertical axis as viewed therein.

The broken line showing of a supporting head member and bracket in Fig. 1 is for illustrative purposes only.

We claim:

The ornamental design for a luminaire, as shown and described,
